UNITED STATES PATENT OFFICE

2,049,824

CARDING MACHINE

Mariano Pla Rosell, Cornellà Barcelona, Spain,
assignor to Compañia Anonima Static, Barce-
lona, Spain

Application June 25, 1934, Serial No. 732,369
In Spain July 8, 1933

2 Claims. (CL 19—98)

It is already known from Spanish Patent No. 127,740 to provide in carding machines curved plates covered with cloth, plush, felt, wool, cotton, silk, rubber, bristles or other suitable materials.

The subject matter of the present invention, which also relates to an improvement in carding machines, permits the cleaning of the carding or covering of the main or carding cylinder of the carding machine during its operation to be avoided or at least reduced to a minimum.

For this purpose means are provided on the carding machine which are completely distinct from those set forth in the above mentioned Spanish patent and which compel the fibres to remain permanently at the tips of the points of the carding of the main or carding cylinder of the carding machine, thereby avoiding the necessity of cleaning the carding frequently.

These means, according to the present invention consist in providing a carding machine with one or more plates having no covering of any kind which are situated concentric with the main or carding cylinder and are arranged in such a manner that they can be electrified. The plate or plates in question may be made of any material which is a good or a bad conductor of electricity.

The said plate or plates, having no covering of any kind, are adapted to become electrified either by the friction of the fibres passing over the main or carding cylinder or by connection with an external source of electrical energy such as a dynamo, an accumulator, a cell, or any other source, and is or are situated at a small distance from the carding of the main or carding cylinder and at any point on its periphery, although in practice it has been found advisable to arrange it in continuation of the dust bars of the carding machine and at a small distance from the doffing roller.

These plates or sheets having no covering of any kind are arranged concentric with the main or carding cylinder and are fixed upon the frame or body of the carding machine and may or

may not be insulated from the mass of the carding machine according to whether they are good or bad conductors of electricity. If these plates are good conductors of electricity they may be connected with an external source of electrical energy in order to electrify them.

In order to make the improvement forming the subject of this invention fully understood, one embodiment is illustrated by way of example in the single figure of the accompanying drawing in which:

1 is the main cylinder or drum; 2 are the dust bars; 3 is the curved plate, having no covering, and which is a bad or good conductor of electricity, and in the latter case is insulated electrically from the carding machine; 4 is the doffing roller; 5 are the strippers; 6 is the frame or body of the carding machine; 7 represents the external source of electrical energy, one of the terminals being coupled to the plate 3, assuming this plate to be a good conductor of electricity. Having now described my invention, what I claim as new and desire to secure by Letters Patent is:

1. In carding machines comprising a carding cylinder, the improvement consisting in mounting a curved plate of good electrical conducting material, insulated from the machine and having no covering of any kind, concentrically with the periphery of the said cylinder, the surface of the said plate being situated so closely to the periphery of the said cylinder that the said plate will come into frictional contact with the fibres treated by the said cylinder during the operation of the machine, whereby the said fibres will be electrified and will be caused to remain at the tips of the points of the carding cylinder, thereby avoiding the necessity of cleaning the carding frequently.

2. The improvement in carding machines, as claimed in claim 1, further comprising a connection between the said plate and a source of electrical energy, whereby the said plate will be placed at a potential.

MARIANO PLA ROSELL. 45
